UNITED STATES PATENT OFFICE.

DON C. BRIAN, OF HOUSTON, IDAHO.

WATER-ELEVATOR.

SPECIFICATION forming part of Letters Patent No. 697,317, dated April 8, 1902.

Application filed August 17, 1901. Serial No. 72,395. (No model.)

To all whom it may concern:

Be it known that I, DON C. BRIAN, a citizen of the United States, residing at Houston, in the county of Custer and State of Idaho, have 5 invented a new and useful Water-Elevator, of which the following is a specification.

This invention is a water-elevator, the object being to provide a simple and effective device for elevating water from a stream, 10 said elevator being propelled by the current of the same stream.

The invention consists in certain details of construction and novelties of combination, all 15 of which will be fully described hereinafter and pointed out in the claims.

In the drawings forming part of this specification, Figure 1 is a view showing the practical application of my invention. Fig. 2 is a front view of the frame supporting one 20 end of the endless chain of buckets. Fig. 3 is a detail perspective view illustrating the position of the bucket as it passes through the stream, the propelling wing or plate being lowered to receive the force of the current. Fig. 4 shows the position the bucket occupies when discharging the water into the chute and also the position it occupies until it enters the stream.

In carrying out my invention I employ a 25 float A, which is anchored in a swiftly-running stream, said float having a derrick or upright frame B arranged thereon, said derrick or frame supporting a chute C, which is intended to convey water to any desired point 30 on the shore.

D represents grooved pulleys journaled at the lower end of the derrick, and E similar pulleys journaled at the upper end of the derrick, parallel cables F passing around said 40 pulleys and also around pulleys E', mounted upon a shaft E², the boxes E³ of which slide vertically in the slotted standards G, firmly embedded in the bottom of the stream, said boxes being connected to a winding-shaft H by means of ropes H'.

A crank H² is arranged upon the end of the shaft H for the purpose of operating the same. Buckets or receptacles I are rigidly secured to the parallel cables F, the said 50 buckets or receptacles being closed at one

end and open at the opposite end, the closed end being preferably wider than the open end, and hinged to the closed end is a blade or wing J, which is adapted to fall by gravity and receive the impact or force of the current. The downward movement of said blades or wings is limited by ropes K, attached to the ends of the said blades or wings and connected to the cables, as shown at K'.

In operation the pulleys E' are lowered so 60 as to bring the lower flight of the endless chain of buckets into the stream, the blades or wings J falling by gravity into the position indicated in Figs. 1 and 3, and thereby receive the force of the current. The current acting upon the closed end of the bucket or receptacle and the blade or wing J forces the lower series of buckets along through the stream around the lower pulley D and up the vertical flight over the pulley E. As each 65 bucket passes over the pulley E it discharges the water into the receptacle C and then passes down the upper flight around the pulleys E' again into the water. In this manner the force of the stream is utilized for the purpose of elevating the water from said stream, and from the chute C the water can be transported to any point or receptacle upon the shore or bank of the stream. By adjusting the pulleys E' the speed of the elevator can 70 be regulated, and, if desired, the pulleys can be raised to a point to stop the operation of the device.

Having thus fully described my invention, what I claim as new, and desire to secure by 80 Letters Patent, is—

1. A water-elevator comprising a float and a fixed frame a derrick arranged upon said float and carrying guide-pulleys, and a chute, the adjustable guide-pulleys arranged in the 90 fixed frame, the endless cables having the buckets attached thereto, said buckets being closed at one end and open at the opposite end, and the hinged blades or wings attached to the closed ends of the buckets, substantially as described.

2. A water-elevator comprising a float, the derrick arranged upon said float and carrying the guide-pulleys, a chute, the vertically-slotted fixed standards, the adjustable shaft 95 100

carrying guide-pulleys and means for adjusting the said shaft vertically, the endless cables passing around the guide-pulleys, the buckets attached to the cables, the closed 5 ends of the buckets being wider than the open ends, and the blades or wings hinged to the closed ends of the buckets and connected to

the cables by ropes or chains, all arranged and adapted to operate substantially as set forth.

DON C. BRIAN.
